STEAM TURBINE CASING AND METHOD OF
MANUFACTURING THE SAMEHans P. Dahlstrand, Wauwatosa, Wis., assignor
to Allis-Chalmers Manufacturing Company,
Milwaukee, Wis., a corporation of Delaware

Application August 23, 1933, Serial No. 686,374

13 Claims. (Cl. 29—148.2)

This invention relates to an improved casing for a steam turbine and to the method of manufacturing the same.

The casings or cylinders of steam turbines are generally formed in separate upper and lower sections bolted together along a longitudinal plane. As usually made heretofore, each of these sections is cast integrally and is provided with cored passages for admitting or withdrawing steam at various positions along the turbine axis. During the casting operation, the cores which form these passages become solidified to such extent that it is difficult and expensive to remove them from the passages in the finished casting. To facilitate the removal of the cores, special openings are provided in the casing which openings must be closed in a permanent manner after the cores have been removed. Further, casings of this nature having inner and outer walls separated by cored passages are difficult to cast successfully, in that the flow of molten metal into the complicated passages of the mold may not take place uniformly and the cooling of the various irregular sections of the casting may occur unequally, resulting in blow holes, shrink cracks, or other imperfections in the casting.

It is an object of the present invention to provide a steam turbine casing that may be manufactured readily and inexpensively and that is of permanent and rigid construction.

A further object of the invention is to provide a method of manufacturing a steam turbine casing whereby a rigid unitary structure having the usual steam passages is made without using cores to form the passages in the casing walls.

According to the present invention, the upper and lower halves of a turbine cylinder or casing are each formed of an outer casing wall cast in one piece and an inner casing wall cast in separate curved sections or ring segments which are secured within the outer wall in such manner as to provide the required steam passages therebetween. For supporting the inner wall segments, the outer wall is provided with inwardly projecting supporting elements. Each of the inner wall segments is provided with an opening by means of which a shrink-fit engagement with the corresponding supporting element is effected. The inner wall segments may be additionally secured to the supporting elements by welding or they may be secured entirely by welding without the shrink-fit engagement.

The foregoing and other objects of the invention, which will become apparent from the following parts of this specification taken in con-

junction with the accompanying drawing, may be accomplished by the embodiments of the invention illustrated in the several views thereof by way of example, of which:

Fig. 1 is a view in vertical longitudinal section of portions of a steam turbine casing embodying the invention, parts of the inner casing being broken away to reveal the supporting elements on the inner surface of the outer casing;

Fig. 2 is a view in transverse section of the 10 turbine casing taken on the plane represented by the line II—II in Fig. 1;

Fig. 3 is a view similar to Fig. 2 but taken on the plane represented by the line III—III in Fig. 1; and

Fig. 4 is a view in vertical longitudinal section of a portion of a turbine casing embodying a modification of the invention, part of a turbine rotor being shown in operating position within the casing.

The steam turbine casings or cylinders shown in the drawing are divided, as is the usual practice, into upper and lower half parts or sections 10 and 11, respectively, which are joined together in a horizontal longitudinal plane.

Referring to the embodiment of the invention shown in Figs. 1, 2 and 3, the upper and lower casing sections 10 and 11 each comprises an outer casing shell or wall section 12 preferably formed in a single piece by casting, and an inner casing shell or wall section formed by a plurality of separately cast ring segments 13 positioned within the outer wall sections 12 in such manner as to provide the required steam passages 14 therebetween.

For supporting the inner wall segments 13, the outer wall 12 is provided with inwardly projecting supporting elements, which may be clearly seen in the upper portion of Fig. 1. These inner wall supporting elements comprise circumferentially arranged ribs or webs 15 that are accurately machined on their inner edges to provide inwardly extending tongues 16 of predetermined dimensions. The tongues 16 are each provided at one side with an undercut flange 17 which is shown greatly exaggerated in the drawing to illustrate its function. Actually the flange 17 is formed by undercutting the tongue 16 a few thousandths of an inch only.

Each of the ring segments 13 forming the inner wall of the turbine casing is provided in its periphery with a circumferential groove 18 complementary to and adapted to receive the tongue 16 of the cooperating supporting web 15, but of slightly smaller dimensions. The groove 18 is

likewise provided with a flange 19 that is formed by slightly undercutting one side of the groove and that is adapted to interlock with the flange 17 of the cooperating web.

- 5 In assembling the ring segments 13 within the outer wall section 12, each of the ring segments is heated to expand the groove 18 therein a sufficient amount to admit the cooperating tongue 16 of the supporting web 15. With the groove 18 10 thus expanded, the flange 17 of the tongue 16 will pass the complementary flange 19 in the groove 18 and permit the ring segment 13 to be placed in its proper position within the outer wall 12 with the flanges 17 and 19 in overlapped relation. 15 The ring segment 13 is then clamped in position and allowed to cool. As the heated ring segment cools to the temperature of the outer wall 12 the groove 18 shrinks into firm engagement with the tongue 16, thus bringing the flanges 17 and 19 20 into interlocking relation and firmly securing the inner wall ring segment to the inwardly projecting web 15.

Each of the ring segments 13 may be further secured to the cooperating web 15 by forming deposits 20 of weld metal in openings that extend through the ring segment into communication with the groove 18 and the inner surface of the supporting web 15.

The grooves 18 are preferably formed in the 30 middle of each ring segment 13 in order that it may be symmetrically supported along one line only upon the cooperating supporting web 15. However, in supporting certain of the ring segments, it is necessary to position the groove 18 35 near one edge of the segment in order to provide a steam passage 14 of the required dimensions between the ring segments and the outer wall 12 of the casing. In such instances the ring segments 13 are additionally supported and positioned, as illustrated by the end segments in Fig. 1 and in Fig. 2, by inwardly projecting bosses 22 on the outer wall 12 which engage each ring segment near the edge thereof farthest from the supporting web 15.

45 The inner surfaces of the bosses 22 are accurately machined to cooperate with complementary machined surfaces on the peripheries of the ring segments 13. During the assembling process, the bosses 22 assist in properly positioning the ring segments when they are fitted into the outer wall of the casing in heated condition. During operation of the turbine the bosses 22 prevent outward deflection of the ring segments 13 in the event that they expand from heating at a rate 50 different from the rate of expansion of the outer wall 12.

In the modification of the invention illustrated in Fig. 4 the inner wall of the turbine casing is formed by ring segments 23 which are fitted 60 between inwardly projecting webs 24 of the outer walls of the casing halves and secured thereto by welding only. Preferably, the ring segments 23 are securely attached at each edge to the adjacent web 24 by a deposit 25 of weld metal. However, if a considerable difference in expansion is 65 to be expected between the inner and the outer walls of the casing, the ring segments 23 may be secured in position by welding at one edge only, as illustrated by the rings at the left end of the 70 turbine casing in Fig. 4, leaving the other edge free to move relative to the adjacent web 24. The free edge of the segment may be supported by bosses 22 extending inwardly from the outer wall as in the case of the end ring segments in 75 Figs. 1 and 2.

The turbine casings herein described may be manufactured expeditiously and inexpensively without the difficulties usually encountered in forming complicated castings and in removing from such castings the cores necessary to form 5 steam passages therein.

Although the specific embodiments of the invention illustrated by way of example have been described in detail in order to fully disclose the invention, it is to be understood that various 10 modifications of the structures shown may be made by those skilled in the art without departing from the spirit and scope of the invention as defined in the subjoined claims.

It is claimed and desired to secure by Letters 15 Patent:

1. The method of making a steam turbine casing having steam passages therein, comprising forming an outer casing in a plurality of complementary sections having inwardly projecting 20 supporting elements, forming inner casing sections adapted to be carried within said outer casing sections in position to form steam passages therebetween and having openings complementary to said supporting elements, heating said 25 inner casing sections to expand said openings, shrinking said inner casing sections on to said supporting elements, and welding said inner casing sections to said supporting elements.

2. The method of constructing a steam turbine 30 casing, that comprises casting a pair of complementary outer casing sections having inwardly extending projections, forming a plurality of inner casing sections having grooves complementary to said projections and adapted to be carried within 35 said outer casing sections, fitting said inner sections within said outer sections by shrinking said grooved sections on to said projections, and further securing said inner sections within said outer sections by welding.

3. The method of manufacturing a steam turbine cylinder having steam passages therein, that comprises casting the outer casing wall in two halves divided longitudinally and having spaced internal circumferential webs, machining said 45 webs to provide inwardly projecting circular tongues of predetermined dimensions, forming half rings to constitute an inner casing wall, machining grooves in the peripheries of said half rings complementary to but slightly smaller than 50 the tongues in said outer casing, heating said half rings to expand said grooves, fitting said heated half rings into said outer casing halves in position to form steam passages therebetween and with said expanded grooves engaging said 55 tongues, cooling said half rings to shrink said grooves into clamping engagement with said tongues, and welding said rings to said casing webs.

4. The method of making a steam turbine cas- 60 ing, that comprises forming an outer wall in a plurality of longitudinally divided complementary sections each provided with an inwardly projecting circumferential rib, machining an undercut flange in said rib, forming an inner wall in 65 arcuate sections, machining in each section a circumferential groove shaped complementary to and adapted to cooperate with the inwardly projecting rib of the corresponding outer wall section, heating said inner wall section to expand 70 the groove therein, fitting said expanded groove over the complementary rib to place the inner wall section in predetermined position within the outer wall section, and then permitting the inner wall section to cool to shrink the groove therein 75

into firm engagement with the rib of the outer wall section.

5. The method of making a steam turbine casing, that comprises forming an outer wall in a plurality of longitudinally divided complementary sections each provided with an inwardly projecting circumferential rib, machining a tongue having a shallow undercut flange in said rib, forming an inner wall in arcuate sections, machining in each of said sections a circumferential groove shaped complementary to and adapted to cooperate with the inwardly projecting rib of the corresponding outer wall section, drilling welding holes through said inner wall section in communication with said groove, heating said inner wall section to expand the groove therein, fitting the expanded groove over the complementary tongue with the undercut flanges thereof overlapping to place the inner wall section in predetermined position within the outer wall section, permitting the inner wall section to cool to shrink the groove therein into firm interlocking engagement with the tongue of the outer wall section, and securing said inner wall section to said rib by welding it thereto through said welding holes.

6. A steam turbine casing, comprising an outer wall including a plurality of complementary parts each having inwardly projecting circumferential ribs, and an inner wall including a plurality of arcuate segments corresponding in angular extent to the parts of the outer wall and each having a groove complementary to the corresponding rib, said inner wall segments being positioned within said outer wall parts with the grooves therein in rigid engagement with the corresponding ribs of the outer wall parts.

7. A steam turbine casing, comprising an outer shell including a plurality of complementary parts, an inner shell including a plurality of arcuate segments disposed within said outer shell, and a body of fused weld metal securing each of said inner shell segments to said outer shell.

45. 8. A steam turbine casing, comprising an outer shell including a plurality of longitudinally divided complementary sections each provided with an inwardly projecting circumferential web having an undercut flange, an inner shell including arcuate sections each having a circumferential groove provided with an undercut flange said groove being complementary to and disposed to cooperate with the inwardly projecting web of the corresponding outer section, and means for securing said sections to said webs.

9. A steam turbine casing, comprising an outer shell, an inner shell formed in a plurality of parts, and a deposit of fused weld metal securing each part of said inner shell within said outer shell along only one line of attachment.

60. 10. A steam turbine casing, comprising an outer shell section having inwardly projecting circum-

ferential webs, a plurality of inner shell segments disposed within said outer shell section in position to form therewith between said webs circumferential steam passages, and means rigidly securing each of said inner shell segments to one of said webs.

11. A steam turbine casing, comprising the combination with an outer shell section having a plurality of inwardly extending circumferential ribs and a plurality of inwardly extending bosses spaced from said ribs, of a plurality of inner shell segments disposed within said outer shell section in engagement with and positioned by said inwardly projecting ribs and bosses and forming between said ribs circumferential steam passages, and means securing each of said inner shell segments to one of said ribs.

12. A steam turbine casing of the type divided longitudinally into separable parts and having formed therein circumferential steam passages, comprising a plurality of complementary one-piece outer shell sections each having spaced integral inwardly projecting circumferential ribs each rib presenting at its inner end a tongue provided at one side with an undercut flange, and a plurality of arcuate inner shell segments corresponding in angular extent to the outer shell sections each presenting in its outer surface a groove complementary to the flanged tongue of one of said ribs, said inner shell segments being mounted within said outer shell sections with the groove of each inner shell segment rigidly engaging the complementary tongue of its cooperating rib and disposed in position to constitute with said rib and other portions of the outer shell a circumferential steam passage.

13. A steam turbine casing of the type divided longitudinally into separable parts and having formed therein circumferential steam passages, comprising a plurality of complementary one-piece outer shell sections each having spaced integral inwardly projecting circumferential ribs each rib presenting at its inner end a tongue provided at one side with an undercut flange, a plurality of arcuate inner shell segments corresponding in angular extent to the outer shell sections each presenting in its outer surface a groove complementary to the flanged tongue of one of said ribs and having spaced openings extending radially from said groove inwardly through the segment, said inner shell segments being mounted within said outer shell sections with the groove of each inner shell segment rigidly engaging the complementary tongue of its cooperating rib and disposed in position to constitute with said rib and other portions of the outer shell a circumferential steam passage, and a deposit of fused weld metal in each of said openings in said inner shell segments rigidly uniting each inner segment to its cooperating rib.

HANS P. DAHLSTRAND.
